UNITED STATES PATENT OFFICE.

D. B. ROGERS, S. ROGERS, AND L. ROGERS, OF PITTSBURG, PENNSYLVANIA.

IMPROVEMENT IN CULTIVATORS.

Specification forming part of Letters Patent No. 19,584, dated March 9, 1858.

To all whom it may concern:

Be it known that we, D. B. ROGERS, SEYMOUR ROGERS, and LUMAN ROGERS, of the city of Pittsburg, county of Allegheny, State of Pennsylvania, have invented new and useful Improvements in the construction of Cultivators; and we do hereby declare the following to be a full and exact description thereof, reference being had to the accompanying drawings, forming a part of this description, in which—

Figure 1 represents sectional pieces of the frame to hold the tooth. Fig. 2 represents the cultivator-tooth. Fig. 3 represents the same pieces seen in Fig. 1 brought together with the cultivator-tooth between them, and shows the manner of securing the tooth in the frame. Fig. 4 represents the gage-irons separate, and Fig. 4' the same put together, as when in use. Fig. 5 represent the braces and spring-clamp. Fig. 6 represents the standards. Fig. 7 represents a cultivator complete, showing the application of our improvements in the construction thereof, and shows the arrangement of the braces, standards, clamp, and gage-irons.

The nature of our invention consists in the following:

First. In forming the frame of a cultivator, or that part thereof which holds the teeth, of two pieces of iron or other suitable material, in which we form semicircles or concavities, so that when said pieces are brought together by bolts or other means the semicircles therein shall form a circular socket for holding the cultivator-tooth. This will be readily understood upon reference to Figs. 1 and 3, where A A represent the pieces with the semicircles formed therein at a a, Fig. 1, and Fig. 3 represents the same pieces brought together, holding the cultivator-tooth in the circular socket b, formed by the semicircles a a aforesaid. This construction is not merely for the object of forming a socket for inserting and holding the cultivator-tooth, but also for the object of receiving them in such a manner that we are enabled to turn the same therein when desired to set the points thereof straight forward in a line parallel with the center line of draft. This object is very desirable in an expanding cultivator, where, as the sides thereof are thrown outward or drawn inward, the points of the teeth in the same are (unless they can in some

way be set as above described) thrown out of a straight line of draft, and consequently do not perform their full purpose.

Second. It also consists in constructing the cultivator-tooth of thin or plate metal with its foot or lower part of the ordinary shape; but the upper end we bend around in a circle, so that it forms a round, hollow shank, as shown in Fig. 2, which represents the cultivator-tooth, d being the shank of the tooth, and C the foot. This construction is for the purpose of obtaining a light but strong tooth and at the same time we have a construction (from the circular form of the shank of the tooth) whereby we are enabled to turn the tooth in its socket when desired, as and for the purposes just above described.

Third. The nature of our invention consists further in the construction of the gage-irons and spring-clamp; also the arrangement of them, together with the braces and standards.

First. The construction of the gage-irons and spring-clamp is as follows, reference being had to Figs. 4, 4', and 5. The gage-irons j, which are for the purpose of expanding and contracting the cultivator, we make in the usual way, with the exception that we flatten and widen out one end of each, and then of the part thus widened out we turn down each edge at about right angles to form a groove, as seen at letters X, Fig. 4, which grooves, as is seen in this figure, we form on reverse sides of the irons, so that upon bringing them together the groove of one iron will receive the body of the other, as represented at letters K, Fig. 4'. The spring-clamp Q, Fig. 5, is for the purpose of clamping the above gage-irons to hold them at any desired point of contraction or expansion of the cultivator, and is constructed as follows: The lower end of one of the braces, h, Fig. 5, is first bent so as to stand perpendicularly, and then a portion of this part is so bent upward that its edges are parallel with the edges of the other portion, and present a figure somewhat similar to the letter U. We then put a hole through the upper parts of this figure for the purpose of inserting a bolt, by which we are enabled to draw them together when desired to clamp or fasten the irons, and thus the clamp is completed. We do not confine ourselves to making this clamp from one end of one of the braces, as

it may be made from a separate piece, and yet effect the same object.

Second. The arrangement of the gage-irons, spring-clamp, braces and standards will be seen in Fig. 7, and is as follows: The gage-irons *jj*, at their outer ends, are attached to the inside of the back end of the cultivator-frame *A A*, the one to one side and the other to the opposite side. Their inner ends are then brought together, the groove of one receiving the body of the other, as before described. In this position, while they support themselves vertically, they keep the cultivator-teeth *c* in an upright position by holding the frame firmly, so that it cannot twist, and also render unnecessary a middle or third beam or piece to a cultivator used in the ordinary construction of cultivators. To hold the irons at any desired point of expansion or contraction of the cultivator, instead of putting holes through and bolting them, as in the usual way, we apply our spring-clamp *Q*, above described, through which said irons pass, as seen in Fig. 7, and by means of the bolt *S*, which passes through just above and crosswise of the gage-irons *jj*, we can draw the clamp together and thus clamp and hold firmly the gage-irons at any point

desired. The braces *h* then extend upward from the gage-irons *jj*, and diagonally to the handles *f f*, to which they are attached by the bolts *i i*, at which point and by the same bolts the upper ends of the standards *g g* are secured, their lower ends being attached to the sides of the cultivator-frame *A A* by the bolts *m*. This arrangement of the braces and standards presents a figure somewhat similar to the letter **M**. The arrangement of these pieces in connection with the gage-irons and clamps renders the whole very substantial.

Having thus described our invention, what we claim, and desire to secure by Letters Patent, is—

The combination of teeth, braces, standards, spring-clamp, and gage-irons with the frame of a cultivator, the whole being constructed and arranged in the manner and for the purposes herein set forth.
